CLAIM

The ornamental design for a door lock guard, substantially as shown and described.

DESCRIPTION

FIG. 1 is a front and side perspective view of a door lock guard showing my new design in the closed position, the broken line showing of a padlock are for illustrative purposes only;

FIG. 2 is a bottom plan view thereof, in the open position and the broken lines showing a door knob are for illustrative purposes only;

FIG. 3 is a front elevational view thereof;

FIG. 4 is a side elevational view thereof, the opposite side being substantially identical.

Fig. 1.

Fig. 2.

Fig. 3.

Fig. 4.
